UNITED STATES PATENT OFFICE.

HARVEY M. WOOD, OF LOS ANGELES, CALIFORNIA.

SAW-CLAMP.

932,224.

Specification of Letters Patent. Patented Aug. 24, 1909.

Application filed January 31, 1907. Serial No. 354,982.

To all whom it may concern:

Be it known that I, HARVEY M. WOOD, a citizen of the United States, residing at Los Angeles, in the county of Los Angeles and State of California, have invented a new and useful Saw-Clamp, of which the following is a specification.

This invention relates to improvements in clamps for holding saw blades while the same are being sharpened.

Objects of the invention are: to provide a saw-clamp having a comparatively thin and light loose jaw that will conform itself most fully to saw blades of different cross-sectional shapes; to provide an improved collapsible saw-clamp of the kind that can be folded into a compact form for storage in carpenters' chests or elsewhere; to provide a collapsible saw-clamp of the character stated, that is light, strong, cheap to manufacture, easy to apply to and remove from the support therefor, easy to assemble and disassemble, and easy to clamp and unclamp; to provide the clamp with spurs adapted to catch in a support when in use, and to be covered so as not to catch on anything when the clamp is folded; and to provide improved means for holding the parts tight and firmly together when the clamp is folded.

Further objects are to provide a simple means for moving one jaw truly and evenly toward the other to tighten the grip of the clamp on the saw blade.

The accompanying drawings illustrate the invention:

Figure 1 is a side view of the clamp folded for storage or transportation. Fig. 2 is a perspective view of the clamp in unfolded or operative position, the jaws being shown open ready to receive a saw blade. Fig. 3 is a cross section taken on line x^3-x^3 of Fig. 2, showing a saw clamped in the vise and the mutilated shaft turned part-way toward working position. Fig. 4 is a fragmental perspective view taken from the rear side of the clamp as shown in Fig. 2. The folded position of one of the loop members is indicated by dotted lines. Fig. 5 is a fragmental section on line x^5 Fig. 2. Fig. 6 is an end view of the saw clamp folded. Fig. 7 is a fragmentary view of the jaw-engaging face of the rear bracket.

1 designates the front jaw and 2 the rear jaw. The rear jaw is pivotally fastened to the rear arm of each of the U-shaped jaw-

connecting members or loops 3 and 4 by means of rivets 5 projecting from said arms into a rear bracket 6. Said bracket 6 is secured to rear jaw 2 by any suitable means as by screws 7. The members 3 and 4 constitute means carrying and loosely connecting the jaws so that the jaws are readily adjustable toward and from each other.

The front arms b of loops 3 and 4 pivotally engage studs 8 projecting forwardly from a front bracket 9 fastened to the front jaw 1 by screws 10. Bracket 9 is extended upwardly at each end thereof to form bearings 11 in which is mounted a mutilated cylindrical shaft 12. Said shaft 12 is cut away or recessed about half way through as at 13 to receive each arm b .

By providing a shiftable handle 14 the vise is adapted for ready and convenient use without obstruction caused by the handle, as the same may drop down out of the way as indicated in Figs. 2 and 5 whenever the shaft is properly turned for that purpose either in its clamping or its unclamping position.

In Fig. 3 the handle is so turned as to be in the way, but since the jaw-engaging means is in the form of a mutilated cylindrical shaft it is free to turn so that the handle 14 may be swung on upward from the position shown in Fig. 3 to vertical position where it will drop down to the position shown in Fig. 2, and such rotation of the shaft 12 does not further move the jaw.

14 designates a finger lever or handle for rotating shaft 12 mounted to slide from end to end through a hole 15, said lever being upset or bent at 14' at each end to prevent its complete withdrawal from the shaft.

By reason of arms b being slidable on studs 8, jaw 1 may be moved outwardly when the recesses 13 of shaft 12 are turned outward, said jaw being forced inwardly closing the clamp when the solid portion of shaft 12 is turned outward to engage the arms b . For the purpose of mounting the clamp on a bench or other support, a bent foldable spur 16 is pivoted at each end of the rear jaw 2, the rear bracket 6 being provided with stop portion 17 to arrest said spurs when swung outwardly and upwardly to a horizontal position. When the spurs are in horizontal position, the points thereof extend downward and may readily be driven into a wooden support to hold the clamp in opera-

tive position. When the clamp is to be folded, spurs 16 are turned down to bring the pointed portions thereof safely out of the way under the lower edge of the jaws. 5 Loops 3 and 4 are then swung astride the jaws of the clamp as indicated in solid lines, in Fig. 1 and in dotted lines in Fig. 4. When in this position, said loops keep the jaws closely together and hold spurs 16 snugly 10 against the rear jaw where they are out of the way and cannot scratch the hands or injure other tools in a carpenter's chest.

In mounting the clamp for use, the U-shaped members 3 and 4 are brought into 15 operative position as shown in Fig. 2, the spurs 16 being then extended and driven into support 18 shown in Fig. 3. A saw blade 5 may be placed between the jaws and the shaft 12 may then be rotated by means 20 of finger lever 14 to turn the recessed portions 13 inward and move the solid portions 19 of the shaft outward to act as a cam against the arms *b* thereby to cause a relative movement between the arms *b* and jaw 1 25 to clamp the latter against the saw blade. The tendency of arms *a*, *b* is to spring together as indicated by the short arrows in Figs. 2 and 3.

30 designates adjusting screws near the bends of the jaw, supporting loops 3, and 4. Said screws extend loosely through arms *b* and have a screw threaded engagement with arms *a* so that by turning said screws the opening between the free ends of the 5 loops may be widened or narrowed. The loops are preferably provided along their entire length with outwardly extending flanges 21, best shown in Fig. 2, to strengthen the same.

40 In order that the metallic brackets of the clamp may be conveniently cast or drop forged and readily assembled, the bearings or retainer 11 for shaft 12 are preferably formed as semicircular, rearwardly opening 45 ears as clearly shown in Fig. 2. In these ears the shaft 26 which is straight upon one side and provided with notches or mutilations 13 on the other side, is mounted so as to bear directly against the front face of the 50 front jaw. Supporting loops 3, 4 which constitute combined jaw-connectors and spur-covers are arranged to embrace the jaws and to extend into the notches or mutilations 13 of the shaft when the shaft is in one position 55 with a portion of its straight side in engagement with the front jaw and so that when the shaft is partially rotated and unnotched part thereof will engage the connector or loop and thereby operate to force the jaw away from 60 the limb of the loop thus engaged and toward the other jaw, but during the operation some portion of the straight side of the shaft will engage directly from end to end of the shaft against the front jaw so that the front jaw 65 is forced toward the other jaw by pressure

applied evenly to the front jaw for a considerable distance therealong, —namely, the entire length of the shaft.

A similar construction of bracket, best shown at 17 in Fig. 4, is desirably used for 70 stopping the spurs 16. The rear bracket 6 is provided with a groove 22 to form a bearing for the shank portions of said spurs, each of which is provided with a shoulder 23 in a cavity 24 to retain the spurs in said grooves. 75

It is to be understood that I do not limit myself to the precise construction shown and described, but that any changes made within the scope of the appended claims be within the limits of this invention. In the present 80 embodiment of the invention jaws 1 and 2 are made of wood, but any suitable material may be used.

The mutilated shaft has one side straight and intact from end to end except that it is 85 reduced at each end to form the gudgeons or pivots 25 which are held in the ears 11, and portions 26, 27, of the shaft are cylindrical so that in all positions of the shaft its peripheral surface engages the front jaw. By means of 90 the mutilated shaft and the slideable pivot studs, force is evenly and directly applied to the movable jaw to grasp the saw-blade tightly all along the face of the saw in contact with the jaw.

95 What I claim is:—

1. A saw vise comprising a jaw, U-shaped members, pivots pivoting one arm of each member, another jaw slidably connected by means of pivots with the other arms of said members, such last mentioned pivots, and a mutilated shaft carried by the last-named jaw and arranged with its mutilations in position to receive the last-named arms of said members when in one position, and means 100 to rotate said shaft to bring the unmutilated portion thereof against said arms to move the jaw relative to said arms; said members being adapted to fold along said jaws into position parallel therewith and with said 105 mutilated shaft.

2. A saw-vise comprising a jaw, pivots mounted in the jaw, U-shaped members connected to the pivots, a second jaw parallel with the first jaw, pivots mounted in the 110 second jaw and slidably mounted in the U-shaped members; a shaft carried by the second jaw and having cut-away portions in alignment with the ends of the U-shaped members so that as the shaft is rotated one 115 way the second jaw is moved toward the first and vice versa, said U-shaped members being adapted to fold longitudinally of the jaws; and a handle slidingly mounted through the shaft in a plane parallel with the cut-away portions of the shaft.

3. Two jaws, a mutilated shaft straight on one side and notched on the opposite side, journaled on one of the jaws, means to turn 120 said shaft and means carrying and loosely 125

connecting the jaws and arranged in the mutilations of the shaft to be engaged by the straight portion of the shaft at a portion of its rotation to move one of said jaws toward the other.

4. A saw vise provided with jaws, a foldable supporting spur, clamping means and a member having substantially parallel limbs connecting said jaws and adapted to be moved into one position to cover the spur when folded, and into another position to be engaged by the clamping means.

5. A saw vise provided with jaws and with a foldable spur, U-shaped connecting means pivoted to the jaws of the vise and adapted to engage the spur and the jaws to press the parts together when the connecting means are folded on the jaws.

6. A saw clamp provided with a foldable supporting spur on one of its jaws and with combined foldable jaw connections and spur holders connecting its jaws and comprising a member having substantially parallel limbs adapted to fold on said spurs when the same are folded.

7. A saw clamp provided with four stops on one of its jaws, two spurs pivoted on said jaw to fold thereon and to engage two of said stops when unfolded, loop members con-

necting the jaws and adapted to fold over the ends of said jaws, and to engage said spurs and the other two of said stops when the clamp is folded.

8. In a saw-clamp, a rear jaw, pivots in the rear jaw, supporting means having parallel arms, the rear ones of said arms being connected to the pivots, a front jaw slidably connected to the other arms, shaft bearings in front of the front jaw, a shaft in the shaft-bearings, means on the shaft whereby the front jaw is moved back and forth, and a handle for operating the shaft.

9. A vise comprising front and rear jaws, the former being provided with two forwardly-projecting studs, two loops, each of said loops being fastened to the rear jaw and movably mounted on the front studs, and cam means between said loops and the front face of the front jaw to engage said jaw and a limb of said loop, and means to partially rotate said cam means.

In testimony whereof, I have hereunto set my hand at Los Angeles California this 31st day of October 1906.

H. M. WOOD.
